[57] **ABSTRACT**

A dispensing apparatus for blends of two or more pet-
rols is provided with an interlock linkage connected
between the blend selection device and a stop member
connected to the switch for activating the pump motor
whereby on alteration of the blend selection device
the linkage moves into the path of the stop member,
de-activating the motor, and likewise the blend selec-
tion device is prevented from being operated when the
motor switch is in the 'on' position.

LIQUID DISPENSING APPARATUS FOR BLENDS OF TWO OR MORE LIQUIDS

This is a continuation of application Ser. No. 3,108 filed Jan. 15, 1970 now abandoned.

This invention relates to apparatus for dispensing liquids and is particularly concerned with apparatus for dispensing blends of two or more petrols having different octane ratings.

The blend to be dispensed by such apparatus is normally set by an operator turning a handle or knob on the casing of the pump and, due to the mechanism employed for computing the price of any selected blend, it is desirable for the blend not to be changed during any particular dispensing operation.

This object is achieved with apparatus for dispensing blends of two or more different liquids in accordance with the invention, which apparatus has a blend selection device for actuating means to determine the relative proportions of the liquids of the selected blend and a switch device for activating and de-activating the motor for the main pump or the like wherein an interlock linkage is provided a part of which engages a part of the blend selection device and which is arranged to move on alteration of the selection device into the path of a stop member connected to the switch device, the arrangement being such that the stop member is moved into a position preventing movement of the interlock linkage and hence the blend selection device when the switch is in the "on" position in which the pump motor or the like is activated and is moved to a position permitting movement of the interlock linkage and hence alteration of the blend when the switch device is moved from the "on" to the "off" position.

Preferably the interlock linkage includes a detent member engaging in a selected one of a number of grooves in the periphery of a disc connected to the blend selection device, the position of the grooves and hence the disc determining the blend to be dispensed, the detent member being connected by linkage either to a tongue or similar member which is moved, when the detent member moves out of a groove and onto the periphery of the disc on turning of the disc to change the blend, into the path of the stop member connected to the switch device. This has the additional advantage that the pump motor cannot be switched on unless the detent of the interlock is engaged in a groove and the tongue is out of the path of the stop member and hence the pump cannot be activated unless the apparatus is set to dispense one of the pre-determined blends.

The invention will now be further described by way of example with reference to the accompanying drawings in which:

FIG. 1 is an elevation of the interlock mechanism and the operative parts of the blend selection device and the switch device of an alternative embodiment of apparatus in accordance with the invention;

FIG. 2 is an end elevation corresponding to FIG. 1;

FIG. 3 is a view corresponding to FIG. 1 showing the parts in a position where the blend has not been correctly selected; and

FIG. 4 is a similar view to FIGS. 1 and 3 but showing the apparatus set for a blend and with the switch lever switched "on."

The petrol pump in which the interlock illustrated in the drawings is mounted also includes means to dispense a blend of two petrols in proportions which de-

pend upon the angular position of a blend selection device including a disc 70, the shaft 72 of which is driven by a knob 74 on the outside of the casing, through a shaft 76 and gears 78. The means for proportioning the two liquids can comprise balancing valves or the device 80 forming the subject of our U.S. Pat. No. 3,486,662 which is driven by a gear 82 on the shaft 72. Means (not shown) are also provided computing the price of any delivery of any blend of petrols. A pointer 84 on the end of the shaft 72 indicates on a dial on the casing the blend selected by a user.

In order to facilitate the price computer and to provide a practical system the number of blends which can be dispensed is restricted to 3 together with the possibility of dispensing each of the two petrols alone. The five angular positions of the spindle 72 which set the blend control is determined by the engagement in notches or grooves 86 formed in the periphery of the disc 70 of a roller 88 forming a detent member.

The roller 88 is pivotally mounted by means of a bracket 90 to an arm 92 one end of which is pivoted at 94 to the casing of the pump and the other end of which is pivotally connected at 96 to a further linkage arm 98 which extends in a direction approximately parallel to the direction of the movement of the roller 88 into and out from the grooves 86 on the disc 70. The other end of the arm 98 is connected to one end of a lever 100 the other end of which is formed as a bush 102 pivotally connected to the casing and receiving one end of a rod 104 extending at right angles to the plane of the links 92, 98, and 100.

The inner end of the rod 104 which extends across the casing carries a bush 106 having a depending lug 108 which is connected by means of a pin 110 to a depending lug 112 of a further bush 114 pivotally connected by means of a rod 116 to the casing. The end 118 of the rod 104 is a loose fit in the open end of the bush 114.

The pin connection between the levers 108 and 112 reproduces at the inner end of the rod 104 the connection at the outer end and so reduces back-lash during movement of the linkage.

A lever 120, forming an extension of the arm 112, is formed with a nose 122 at its free outer end.

The interlock linkage comprising the arms 92, 98, 100, 108, 112 and 120 together with the rod 104 acts to multiply any movement of the detent roller 88 from its position as shown in FIG. 2 where it is held engaged in one of the grooves 86 by a factor of six.

Whilst the linkage is biased by a spring 124 to the position where the roller 88 is engaged in a groove 86, the roller can, on turning of the disc 70 to change the blend, move onto the periphery of the disc and the nose 122 of the arm 120 of the interlock linkage is then caused to move by that linkage to the position shown in FIG. 3.

The motor for the main pump of the dispensing apparatus is switched on and off on turning of a spindle 126 by means of a handle on the outside of the casing (not shown) and this spindle is connected to a cam 128 having stop faces 130. In the position shown in FIG. 3 the motor is switched off and hence the nose 122 of the linkage arm is permitted to move from the position shown to the position shown in FIG. 3 and hence the disc 70 can be turned causing the detent member 88 to move from one of the grooves in the disc onto the periphery of the disc i.e., to the position shown in FIG. 3

and to then drop into a further groove for the selection of an alternative blend. When the pump motor is switched on the shaft 126 and hence the cam 128 and stop faces 130 are moved in a clockwise direction to the position shown in FIG. 4 in which the stop faces of the cam lie above the nose 122 of the arm 120 of the interlock linkage so that this nose cannot then be moved to the position shown in FIG. 2. The detent roller 88 is then prevented from moving out of the particular groove 86 in which it is engaged and hence the disc 70 cannot be moved to change the blend when the pump motor is switched on.

Equally if the detent has not properly been engaged in one of the grooves 86 on the disc 70 but rather still engages the periphery of the disc as shown in FIG. 3 then the nose 122 remains in the position shown and the cam 128 is prevented from being turned to a position in which the pump motor is switched on due to the engagement of the stop face 130 with the nose 122 which lies across its path. This prevents operation of the apparatus when the blend has not been accurately selected.

Two tapered cheek pieces 132 are attached to the cam 128 and each contacts one of two pins 134 fitted respectively to two arms 136, these being connected to carriers for gear pinions which form part of the calculating mechanism as shown in our U.S. Pat. No. 3,429,480. When the switch lever is moved to the off position the pins 134 ride up the inclined faces of the cheek pieces 132 and move its pinions out of mesh with contrate gear allowing the pinions to be moved up or down. When switch lever is moved to the on position, the pins 134 slide down inclined faces allowing the pin-

ions to remesh with the contrate gears.

I claim:

1. Apparatus for dispensing blends of two or more liquids having a motor-driven pump; a switch device for activating and de-activating the said motor; a blend selection device; variable proportioning means for determining the relative proportions of the liquids of the selected blend, the proportioning means being set by the blend selection device; rotatable disc means connected to the blend selection device and having a number of indentations on its periphery, the angular position of the disc determining the blend to be dispensed; wherein an interlock linkage is provided which comprises: a follower member for engagement with the periphery of the said disc; means mounting the follower member for movement towards or away from the disc; resilient means biasing the follower member into permanent engagement with the disc; a tongue or similar member; a stop member connected to the switch device and having two positions corresponding to the 'on' and 'off' positions of the switch; means mounting the tongue for movement into or out of the path of the stop member; and a linkage connecting the said tongue to the said follower member, the tongue having two positions corresponding to the positions of the follower member, the first position of the tongue, when the follower member is riding on the periphery of the disc, lying in the path of the stop member, so as to prevent the switch being moved to the 'on' position and the second position, when the follower is engaged in an indentation of the disc, lying outside the path of the stop member, so as to permit the switch to be moved to the 'on' position.
